US00D874880S

(12) **United States Design Patent** (10) **Patent No.:** **US D874,880 S**
(45) **Date of Patent:** **** Feb. 11, 2020**

(54) **THERMALLY INSULATING MEMBER**

(71) Applicant: **LIAN YI DESIGN ENTERPRISE CO., LTD.**, Kaohsiung (TW)

(72) Inventor: **Shao-wen Zhang**, Kaohsiung (TW)

(73) Assignee: **LIAN YI DESIGN ENTERPRISE CO., LTD.**, Kaohsiung (TW)

(**) Term: **15 Years**

(21) Appl. No.: **29/604,936**

(22) Filed: **May 22, 2017**

Related U.S. Application Data

(63) Continuation-in-part of application No. 29/516,870, filed on Feb. 6, 2015, now Pat. No. Des. 797,524.

(57) **CLAIM**

The ornamental design for a thermally insulating member, as shown and described.

DESCRIPTION

FIG. 1 is a perspective view of a thermally insulating member showing my new design;

FIG. 2 is a front elevational view thereof;

FIG. 3 is a top plan view thereof;

FIG. 4 is a right side elevational view thereof;

FIG. 5 is a bottom plan view thereof;

FIG. 6 is a rear elevational view thereof;

FIG. 7 is a left side elevational view thereof; and,

FIG. 8 is another front view thereof, shown in an alternate position.

1 Claim, 8 Drawing Sheets
